SELF SHAKING DUST MOP

Filed March 5, 1937

UNITED STATES PATENT OFFICE

2,104,614

SELF-SHAKING DUST MOP

John C. Finfrock, Kansas City, Mo.

Application March 5, 1937, Serial No. 129,273

1 Claim. (Cl. 15—147)

The invention relates to a self-shaking dust mop.

The object of the present invention is to improve the construction of dust mops and to provide a simple, practical and efficient self-shaking attachment for dust mops of strong, durable and comparatively inexpensive construction for pivotally connecting a mop head with a mop handle and for operating the mop to swing the mop head from the under side of the handle to the upper side of the same and back again with a jarring action sufficient to shake from the mop head dust and other accumulation.

A further object of the invention is to arrange the pivotal connection between the mop head and the handle so that when the mop head is swung by the operating mechanism to the upper side of the handle it will swing downwardly automatically by gravity to the under side of the handle thereby simplifying and increasing the ease of operation of the mop to clean the mop head.

With these and other objects in view, the invention consists in the construction and novel combination and arrangement of parts herein-after fully described, illustrated in the accompanying drawing and pointed out in the claims hereto appended, it being understood that various changes in the form, proportion and details of construction, within the scope of the claim, may be resorted to without departing from the spirit or sacrificing any of the advantages of the invention.

In the drawing:—

Fig. 1 is a perspective view of a dust mop constructed in accordance with this invention.

Fig. 2 is a longitudinal sectional view of the same on a slightly enlarged scale, the handle and the operating rod being broken away.

Fig. 3 is a transverse sectional view taken on the line 3—3 of Fig. 2.

Fig. 4 is a detail perspective view of the pivotally mounted plate.

In the accompanying drawing in which is illustrated the preferred embodiment of the invention the self-shaking dust mop comprises in its construction an approximately triangular plate 1 constructed of sheet metal or other suitable material and tapered forwardly or outwardly and provided adjacent its corners with upwardly projecting outwardly extending approximately hook shaped prongs 2 formed integral with the plate 1 and struck up from the plate and spaced from the marginal edge of the plate to permit a marginal binding element 3 of a fibrous mop head 4 to be arranged on the plate between the

same and the said prongs as clearly illustrated in Figs 2 and 3 of the drawing. The fibrous mop head may be constructed of any suitable material and it consists of the said binding element 3 and twisted strands 5. The marginal binding member extends around the marginal portion of the approximately triangular plate 1 and its terminals which are located at the inner or rear edge of the plate 1 centrally of said edge are adjustably and detachably connected by a strap 6 riveted or otherwise secured to one of the terminals of the binding element 3 and detachably engaging a buckle 7 suitably secured to the other end of the binding member. While a strap and buckle connection is illustrated in the drawing any other suitable means may of course be employed for detachably securing the fibrous mop head proper to the plate 1. The fibrous mop head may be readily removed for washing, renewal or repair.

The plate is provided at or near its central portion with a pair of longitudinally disposed bearing brackets 8 consisting preferably of spaced angle plates riveted or otherwise secured to the plate 1 and extending upwardly from the upper face of the said plate 1 and receiving between them an eye 9 of a shank 10 of a mop handle 11 which is pivotally connected with the plate by means of a transverse rivet 12 or other suitable pivot which passes through the eye 9 and pierces the projecting flanges or portions of the bearing brackets adjacent the front ends of the same as clearly illustrated in Figs. 2 and 3 of the drawing. The shank 10 has a slight downward curve to offset the eye 9 from the central longitudinal axis of the handle. This permits the rear portions of the brackets to swing beneath the handle which is reinforced at its front end by a suitable ferrule 13.

The rear portions of the bearing brackets receive between them an eye 14 of an operating rod 15 located beneath and extending along the mop handle 11 and passing through a guide eye 16 thereof. The operating rod is provided in advance of the eye with a depending loop 17 forming a grip or handle and its rear end is bent at an angle in rear of the eye 16 to form a stop lug 18. The mop handle may be held in either hand and the other hand grasps the grip 17 of the operating rod and moves the same outwardly to swing the plate and the mop head from the under side of the mop handle to the upper side thereof when the force of gravity will tend to swing the plate and the mop head downwardly thereby assisting the operator in shaking the mop to remove dust and other accumulation from the fibrous

mop head. The plate and the mop head may be swung upwardly and downwardly with a jarring action sufficient to shake the dust and other accumulation from the fibrous mop head. While 5 the bearing brackets are shown riveted to the pivoted plate they may be fixed to said plate in any other suitable manner.

What is claimed is:—

10 A dust mop including a normally approximately horizontal plate adapted to carry a fibrous mop head, a mop handle pivotally connected at one

end with said plate at the upper face thereof and provided with a guide, and an operating rod also pivotally connected with the plate at a point spaced from the pivotal connection of the mop handle and extending through the guide of the 5 same and provided in advance of the guide with a projecting loop forming a hand grip, said operating rod being bent in rear of the guide to form a stop lug.
